UNITED STATES PATENT OFFICE.

FRANK W. DAVENPORT, OF PROVIDENCE, RHODE ISLAND.

DESIGN FOR A RECORD-SHEET.

SPECIFICATION forming part of Design No. 35,717, dated February 11, 1902.

Application filed January 6, 1902. Serial No. 88,706. Term of patent 7 years.

To all whom it may concern:

Be it known that I, FRANK W. DAVENPORT, a citizen of the United States, residing in the city and county of Providence and State of Rhode Island, have invented and produced a new and original Design for a Record-Sheet, of which the following is a specification, reference being had to the accompanying drawing, forming part thereof.

As shown in this drawing, the leading or material features of my design consist of the curved and straight lines forming the upper part A, the two rectangular pendent portions B B at either end of same, and the blank space C left at the center, each pendent portion being divided into a number of small spaces D, disposed perpendicularly in one

column, and a similar number of larger spaces E, similarly disposed, and each small space being on line with one of the larger spaces 20 and close against it, all as shown.

Having described my invention, what I claim as new, and desire to secure by Letters Patent, is—

The design for a record-sheet, as herein 25 shown and described.

In testimony whereof I have signed my name to this specification in the presence of two subscribing witnesses.

FRANK W. DAVENPORT.

Witnesses:

M. D. WHALEY,
A. E. POTTER.
